graphie m. b. H., Berlin, Germany, a corpora-
tion of Germany

Application August 26, 1933, Serial No. 686,865
In Germany September 6, 1932

2 Claims. (Cl. 250—20)

This invention relates to a new and improved scale or dial for radio-receiver sets.

Scale arrangements are known in the art which comprise station names and in which the point of setting or adjustment is made visible by the aid of a line of light or the like. The disadvantage of such arrangements consists in that when making the set it is hard to tell beforehand what stations will be properly received at the place where the set is set up and used. As a result, difficulties often arise in that a station clearly received at the receiving place is not included on the dial, or else a station for which the receiving conditions are notoriously poor, is included in the list of stations. Another fact is that such dial arrangements may not be used simultaneously for receiver apparatus of different power or performance for the reason that, for instance, for low power receivers the list of stations will be too long, while that of larger power receivers should comprise a greater number of stations.

These difficulties are obviated in the present invention by providing ways and means so that only such stations will be made visible as provide energies at the point of reception adequately large for operating the loudspeaker. An approved form of the invention is illustrated in the accompanying drawing in which Fig. 1 is a plan view of the dial arrangement and Fig. 2 is a circuit diagram showing how the glow lamp which cooperates with the dial arrangement is actuated.

Fig. 1 shows an arrangement of this kind. A transparent screen 1 bearing the station names, is arranged in front of a slotted member 2. In back of the slotted member a gaseous conduction tube or glow-lamp 9 is mounted. By actuation of the master tuning knob or dial 5 of the tuning means, the slotted member 2 is shifted with the setting of the tuning dial by means of the pulleys 4 and the cord drives 3. The output circuit of the power tube 6 (Fig. 2) contains the loudspeaker connection means 7 and the trans-

former 8. A glow-lamp 9 is united with the secondary terminals of the transformer. The arrangement is so tuned that the lamp 9 will flash up or light only when the signal picked up by the receiver is so strong that it will serve to operate the loudspeaker strongly enough.

What I claim is:

1. Station indicating means for a radio receiving set, comprising a transparent screen containing a plurality of station names, a member arranged in back of said transparent screen, said member having an opening therein slightly larger than the space occupied by any one of said station names, means associated with the tuning dial of said radio receiving set for moving said member so that the opening therein may be caused to register with any one of said station names, a source of light mounted at the rear of said member for illuminating a station name on said transparent screen through the opening in said member, and means for energizing said source of light from the output circuit of the power stage of the radio receiving set during intervals when the received signal exceeds a certain critical value. 15

2. Means for indicating the position of the tuning means of a radio receiver, comprising the combination of a stationary transparent screen having a plurality of station names marked thereon, upper and lower pulleys, a control knob 30 connected to one of said pulleys, a belt passing over said pulleys, a member secured to said belt at the rear of said screen and having an opening therein longer and wider than the space occupied by one of said station names, a source 35 of light mounted at the rear of said member and arranged to illuminate a single station name on said screen through the opening in said member, and means for energizing said source of light from the power tube of the radio receiver when 40 the received signal energy exceeds a predetermined value. 25

RUDOLF RECHNITZER.
